UNITED STATES PATENT OFFICE.

JOHN ELLIOT PEIRCE, OF DAYTON, OHIO.

DESIGN FOR A CABINET.

SPECIFICATION forming part of Design No. 24,006, dated February 5, 1895.

Application filed December 24, 1894. Serial No. 532,883. Term of patent 3½ years.

To all whom it may concern:

Be it known that I, JOHN ELLIOT PEIRCE, a citizen of the United States, residing at Dayton, in the county of Montgomery and 5 State of Ohio, have invented and produced a new and original Design for a Cabinet; and I do declare the following to be a full, clear, and exact description of the same, reference being had to the accompanying drawing, 10 forming a part thereof.

The design herein shown and described is for a cabinet.

It has for its object to provide a novel and ornamental cabinet, and possessing its 15 own ornamental and distinguishing features. These features of design consist of a body, of a square-upright form in front elevation, and a quadrangular form in end elevation; the whole surmounted by an open, ornamental 20 frame work; a panel flush with the front of, and extending across the upper terminal of said body; a series of sunken, oblong-rectangular panels, below said panel, and separated from the latter by a strip of rounded 25 molding.

The design is illustrated in the accompanying pictorial reproduction, in which the view, shows in perspective, a cabinet embodying my design.

30 In said view, (A) designates the body portion or the cabinet proper, in the front of which there are three tiers of sunken, oblong-rectangular panels (a), surrounded by a rectangular frame (b) that forms the margin of 35 the front of the cabinet. These tiers of panels are divided by two vertical, and two horizontal strips (c) and (d), and are immediately inclosed by strips (e) and (f).

(B) is a horizontal panel extending across

and forming the upper terminal of the cabinet proper. This panel lies flush with the front of the cabinet, and may contain any ornamental carving.

(g) designates a horizontal strip of molding immediately below the panel (B), and extending around the ends of the cabinet in the same plane. Each of the ends of the cabinet has two sunken panels (C) and (C') which are divided longitudinally by a raised strip (C'').

The top of the cabinet lies on an incline to 50 the front, and forms an obtuse angle with the front and back. The cabinet is surmounted by an ornamental open frame that extends flush with the front thereof, and consists of a plurality of parallel strips (1) (2) 55 (3) and (4) joined by vertical end strips (5) and (6). The two upper parallel strips (1) and (2) have a centrally interposed strip (7).

(8) and (9) designate strips interposed between the inner ends of the lower parallel 60 strips (3) and (4), and the middle portion of the central strip (2).

(10) and (11) designate ornamental brackets occupying the inner corners formed by the meeting of said strips.

65 Constructed in accordance with the above ornamental and characteristic features, the design is readily distinguishable.

What I claim is—

The design for a cabinet herein shown and 70 described.

In testimony whereof I affix my signature in presence of two witnesses.

JOHN ELLIOT PEIRCE.
